Attorney

UNITED STATES PATENT OFFICE

GEORGE H. HAHM, OF METUCHEN, NEW JERSEY

FUEL TANK FOR OUTBOARD MOTORS

Application filed November 19, 1929. Serial No. 408,378.

This invention relates to fuel tanks of out-board motors. Out-board motor engines are extremely hard to start and at times it is impossible to start the engine and sometimes it takes from fifty to seventy-five efforts before the engine will start. This is not only extremely irritating to put it mildly, but often leads to accidents in which the person starting the motor is injured. I have found, after many years of experience with out-board motors, that the trouble is caused by the sweating of the gas tank, moisture gathering on the inside of the gas tank and gradually trickling down into the gasoline and settling to the bottom of the tank. This is particularly due to the fact that the fuel slops around in the interior of the tank and gathers up this water. Furthermore sediment gathers in the bottom of the tank and when an attempt is made to start the motor, the sediment and water pass to the carburetor instead of gasoline. As a consequence, of course, the charge will not explode, the engine misses fire and attempt after attempt must be made until this water has been discharged. If the water gets into the carburetor, it is impossible to start the engine until the water has been gotten rid of.

The object of my invention, therefore, is to provide a fuel tank so constructed that the water which has accumulated within the fuel tank may be discharged before any attempt is made to start the engine and to this end to so construct the gas tank that it is deeper at one point, as for instance at one corner of the tank than it is anywhere else so that the water and sediment will naturally gravitate at this corner and to provide a pet-cock at this corner whereby this sediment and water may be removed, permitting the pure gasoline to pass to the carburetor.

My invention is illustrated in the accompanying drawings, wherein:

Figure 1 is a side elevation of an out-board motor fuel tank constructed in accordance with my invention;

Figure 2 is an end view thereof;

Figure 3 is a view on the opposite end of the tank from Figure 2;

Figure 4 is a sectional view of the globular pet-cock.

Referring to these drawings, 10 designates a fuel tank which in ordinary circumstances will be 11½ inches long by 4¾ inches wide and 3¾ inches deep. The floor 11 of this tank extends downward toward one corner of the tank as shown and from this low corner of the tank extends a pipe 12 connecting with a hollow pet-cock body 13 having a tap 14 at its lower end. Above this pet-cock body 13, a pipe 15 extends to the carburetor provided with a tap or valve 16. I do not wish to be limited to the particular form of pet-cock nor to the particular form of valves except as stated in the claims. This gas tank may be supported by two arms extending out from the muffler and fastened to the same. I do not wish to be limited to this, however.

By means of my device all sediment or water in the fuel tank gathers in the pet-cock body. Before starting the engine, the tap 14 is opened and one or two tablespoonfuls of the mixture of water and foreign matter are drawn off. The tap 14 is then closed and the valve to the carburetor is then opened and pure fuel is then delivered to the carburetor and the engine will immediately start up upon being cranked assuming that the spark plug is in working order and the gas mixture and spark have been properly adjusted.

I have found in actual practice that the numerous failures of out-board motors to start can be entirely overcome by using this tank and that 90% of starting trouble is eliminated with my device.

I claim:

1. The combination with an out-board motor, of a fuel tank therefor having a flat bottom inclined downward and laterally to one corner of the tank whereby one corner of the tank is disposed at a point lower than any other point of the bottom, a hollow pet-cock body having a pipe connection to the lowest portion of the bottom to thus permit it to receive sediment and water, the lower end of this pet-cock body having a manually operable drainage valve and a pipe connection to the carburetor leading from the pipe connec-

tion to the hollow pet-cock and provided with a valve.

2. A gas tank for outboard motors having a bottom so formed as to provide at one corner of the tank a depressed water and sediment collecting portion forming the lowest portion of the tank, a pipe extending downward from this depressed portion, a pet cock connected to the lower end of the pipe, the pet cock being formed to provide a water collecting chamber, and a carbureter connection extending from the said pipe above the water collecting chamber formed by said pet cock and below the bottom of the tank, said carbureter connection having a valve.

In testimony whereof I hereunto affix my signature.

GEORGE H. HAHM.
